DESIGN FOR A DOOR FACE PLATE FOR WICKETS

William Frankel, New York, N. Y.

Application August 4, 1937, Serial No. 70,844

Term of patent 7 years

To all whom it may concern:

Be it known that I, William Frankel, a citizen of the United States of America, residing at New York city, in the county of New York and State of New York, have invented a new, original, and ornamental Design for a Door Face Plate for Wickets, of which the following is a specification, reference being had to the accompanying drawing, forming a part thereof, and in which

Fig. 1 is a front view in elevation of a door face plate for wickets embodying my new design; and

Fig. 2 is a horizontal section taken along the line 2—2 of Fig. 1.

I claim:

The ornamental design for a door face plate for wickets as shown and described.

WM. FRANKEL.
